UNITED STATES PATENT OFFICE.

WILLIAM F. HENDRY, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE AND METHOD OF MANUFACTURING THE SAME.

Application filed July 14, 1920. Serial No. 396,146.

This invention relates to an electrode structure for electron discharge devices and to methods for assembling the same.

An object of this invention is to provide a compact and rugged electrode structure for an electron discharge device of such a type that the electrodes of the structure may be assembled and permanently lined up with respect to each other prior to attaching the structure to any part of the containing vessel of the device.

For convenience, this invention will be illustrated and described in connection with an electron discharge device of the three-electrode type, comprising an anode, a cathode and a controlling or grid electrode, enclosed in an evacuated vessel. The electrode unit, hereinafter described in detail as constituting one form of structure to which the assembling methods of this invention may be applied, comprises a cylindrical anode supporting at either end a block of insulating material. The grid and cathode are located within the anode and are supported by wires fastened to the two blocks of insulating material. The electrode unit, comprising the three electrodes and the two blocks of insulating material, is supported in the vessel by having the anode terminate in a metallic collar, which surrounds an inwardly projecting neck of the containing vessel and which may be held thereto by friction.

The method employed in assembling such a structure, so that the three electrodes are assembled and permanently lined up with respect to each other prior to attaching them to any part of the containing vessel, comprises the steps of attaching the filament or cathode to one of the blocks, attaching the cylindrical anode to this block, inserting the grid between the anode and filament, and subsequently attaching all three electrodes to the second insulating block. The electrode unit may then be suitably attached to a glass stem and the stem sealed to the containing vessel.

This invention will be better understood by reference to the following detailed description taken in connection with the accompanying drawing, in which Figure 1 represents an embodiment of this invention employing a flat cylindrical anode, and Figure 2 represents a modification of

Figure 1 in which a circular cylindrical anode is employed.

Referring to Figure 1, the electron discharge device disclosed therein comprises a containing vessel 5 of glass, which has an inwardly projecting stem or neck 6. Surrounding the stem 6 and held thereto by friction is a collar 7, to which are fastened two T-shaped members 8 and 9 which serve as supports for the flattened cylindrical anode 11. Fastened to opposite sides of the anode 11 are two posts which have projections 12, 13 and 14, 15, which are employed for supporting insulating blocks 17 and 18, respectively. These blocks are preferably made of "lavite."

Within the anode, and supported by the two blocks 17 and 18, are the helical grid electrode 20 and the cathode 21. The helical grid 20 is fastened to a plurality of longitudinal rods or rigid wires 23, 24, 25 and 26. Rods 24 and 25 are rigidly set in block 18 in a suitable manner, in order that the grid may be supported thereby and properly positioned with respect to the cylindrical anode 11. Rods 24 and 25 are shown as projecting through apertures in the block 17. It has been found preferable to have the apertures in block 17 of such a diameter that the wires 24 and 25 fit loosely therein, so as to allow for the ready expansion or contraction of the grid, due to changes in its temperature. The lower ends of filament 21 are held in position by the hooked wires 30, which are rigidly attached to the lower "lavite" block 18. The loops of the filament adjacent block 17 are supported by hooked wires 32, which pass loosely through apertures in block 17. The ends of wires 32, on the side of block 17 opposite the filament, are connected to coiled springs 34, whereby the filament is resiliently supported.

In order that electrical connections may be made with the anode, cathode and grid, lead in wires 40, 41, 42 and 43 are provided; lead 43 being connected to the anode, lead 40 to the grid and leads 41 and 42 to opposite terminals of the cathode.

The type of electrode structure described above, in which the cathode and grid are supported between two blocks of insulating material, which are fastened to and supported by projections arising from the anode, is not a part of this invention but is de-

scribed and claimed in the patent to William G. Housekeeper, No. 1,536,855 issued May 5, 1925; also the manner of resiliently supporting the cathode described above is 5 the invention of another and is described and claimed in a copending application of Paul M. Watrous filed November 25, 1919, Serial No. 340,455.

The steps of the method employed in assembling such a structure, so that the three electrodes are assembled and permanently lined up with respect to each other prior to attaching them to any part of the containing vessel, are as follows:

- 15 1. The filament-supporting wires 30 are fastened to the "lavite" block 18.
2. The filament is connected in the desired manner to the wires 30.
3. The anode electrode 11 is placed around the filament and projections 14 and 15 are fastened to block 18.
- 20 4. The grid electrode is inserted between the filament and the anode.
5. "Lavite" block 17 is placed in position and projections 12, 13 and wires 24 and 25 are inserted therein.
- 25 6. The hooked wires 32 are then passed through apertures in block 17 and are engaged with the loops of the filament 21.
- 30 7. The upper ends of these wires 32 may then be fastened to the coil springs 34.
8. The collar 7 is forced on the stem 6.
- 35 9. Lead in wires 40 to 43 are connected to the proper electrodes.

Figure 2 illustrates a modification of Figure 1 in which a circular cylindrical anode 50 is employed. The anode 50 is supported as in Figure 1 by a metallic collar 51, surrounding the neck 52 of the containing vessel 53. The open ends of the anode 50 are closed by two circular blocks of insulating material 55 and 56. The anode 50 fits snugly against the shoulders 57 and 58 of blocks 56 and 55. Blocks 55 and 56 are fastened to the cylindrical anode in any suitable manner, such as by lugs or clips shown at points 60 and 61, for example. The anode surrounds the cylindrical grid electrode 62, which has a plurality of its supporting wires 64 fitting snugly against shoulders 66 and 67 of blocks 55 and 56. The distance 45 between shoulders 57 and 67 and between shoulders 58 and 66, is such as to provide the proper spacing of the grid with respect to the surrounding anode 50. The filament electrode 68 of the device is supported at one end by wires 69 and 70, which pass through insulating block 56, and is supported at the other end by the hooked wire 72, which resiliently supports the cathode 68 in a manner similar to that already described for Figure 1.

The electrode unit illustrated in Figure 2 may be assembled in the manner previously described under Figure 1, so that the electrode unit will be mounted on the neck 52 of the vessel only after the electrodes of the 70 structure have been assembled and permanently lined up with respect to each other.

It is obvious that the method above described for assembling an electrode structure prior to attaching the structure to any 75 part of the containing vessel, may be applied to specific electrode structures differing from those above described, without departing in any wise from the spirit of this invention as defined in the appended claims. 80

What is claimed is:

1. A method of manufacturing electron discharge devices which comprises supporting one electrode from a standard, attaching insulating members to either end of said electrode, arranging a plurality of electrodes within said first electrode and supporting said last named electrodes solely from said insulating members. 85

2. A method of manufacturing electron 90 discharge devices which comprises supporting an electrode from a standard, attaching insulating members to either end of said electrode, arranging a plurality of electrodes within said first electrode, supporting said last named electrodes solely from said insulating members and attaching said standard to a stem. 95

3. A method of manufacturing electron 100 discharge devices which comprises arranging a pair of electrodes within a third electrode, insulatingly supporting said first two electrodes solely from said third electrode and disposing the electrode assembly wholly within a glass containing vessel. 105

4. The method of manufacturing an electron discharge device composed of an enclosing vessel having a stem, a plurality of electrodes and insulating members, said method consisting of assembling the cathode on one insulating member, inserting said cathode within the anode and rigidly attaching said insulating member to one end thereof, inserting a grid electrode between the cathode and anode and attaching to said insulating member, slidably supporting the free end of said cathode and grid in a second insulating member rigidly attached to the other end of the anode, and thereafter supporting said assembly from the 110 stem of the enclosing vessel. 115

5. An electron discharge device comprising a containing vessel, an anode within said vessel, a plurality of electrodes within said anode, a supporting connection from said anode to a wall of said vessel, a pair of insulating members rigidly attached to the ends of said anode, and means for supporting said electrodes from said members. 120

6. An electron discharge device compris- 125

- ing an enclosing vessel containing a cathode, a control electrode and an anode surrounding said cathode and control electrode, a plurality of blocks of insulating material carried by said anode and located at opposite ends thereof, and means for supporting said cathode and control electrode solely from said blocks. 5
7. An electron discharge device comprising an enclosing vessel containing a cathode, a cylindrical anode, a plurality of blocks of insulating material rigidly attached to said anode and covering the ends thereof, and means for supporting said cathode substantially entirely from said blocks of insulating material. 10
8. An electron discharge device comprising an enclosing vessel containing an anode, a cathode and a control electrode, a pair of supports secured to said anode at opposite ends thereof and means for supporting said cathode and control electrode substantially entirely from said pair of supports. 20
9. An electron discharge device comprising an enclosing vessel containing a plurality of electrodes, a pair of supports attached to one of said electrodes, and a plurality of other electrodes supported substantially entirely from said supports. 25
- 30 10. An electron discharge device comprising an enclosing vessel containing a plurality of electrodes, a pair of supports attached to one of said electrodes, and a plurality of other electrodes supported substantially entirely from said supports, said other electrodes being spaced between said pair of supports.
11. An electron discharge device comprising an enclosing vessel containing a cathode, a grid surrounding said cathode, an anode surrounding said grid, means for supporting said anode within said vessel, said anode being cylindrical in form, a plurality of blocks of insulating material attached to said anode, said cathode and grid being spaced between said blocks and supported thereby. 40
- 50 12. An electron discharge device comprising a vessel containing a tubular anode, means for supporting said anode within said vessel, a cathode cooperating with said anode, a block of insulating material at either end of said anode of substantially the same size as said ends, said blocks being rigidly fastened to said anode, and means for supporting said cathode from said blocks. 55
- 60 13. An electron discharge device comprising an enclosing vessel containing a tubular anode, means for supporting said anode
- within said vessel, a stopper of insulating material rigidly attached at either end of said anode for substantially closing said ends, and a cathode spaced between said stoppers and supported thereby. 65
14. An electron discharge device comprising an enclosing vessel having a stem, a cylindrical output electrode supported thereby, a cathode within said electrode and extending lengthwise thereof, a support attached to said output electrode for said cathode, and a grid between said cathode and output electrode carried by said support. 70
15. An electron discharge device comprising an enclosing vessel having a stem, a cylindrical output electrode supported thereby, a cathode within said electrode, a pair of supports carried by said output electrode and connected to opposite ends of said cathode, a control electrode surrounding said cathode within said output electrode and also carried by said supports, and an envelope sealed to said stem. 75
16. An electron discharge device comprising a vessel having an inwardly projecting neck, an anode supported by a collar surrounding said neck, blocks of insulating material at opposite ends of said anode, and cathode and control electrodes supported by said blocks. 80
17. An electron discharge device comprising an enclosing vessel having a stem, an anode supported by a metallic collar surrounding said stem, cathode and control electrodes surrounded by said anode, a block of insulating material rigidly attached at either end of said anode and supporting wires engaging said blocks for supporting said control electrode and cathode. 90
18. An electron discharge device comprising an enclosing vessel having a stem, an electrode supported by a collar surrounding said stem, a block of insulating material rigidly attached at either end of said electrode, a second electrode, and means for supporting said second electrode between said blocks. 100
19. An electron discharge device comprising an enclosing vessel having a reentrant stem, an electrode assembly within said vessel comprising a pair of insulating members and at least two electrodes, said insulating members being affixed to one of said electrodes, a collar on said stem, and means for supporting said assembly substantially wholly from said collar. 110
- In witness whereof, I hereunto subscribe my name this 9th day of July A. D., 1920.

WILLIAM F. HENDRY.
